UNITED STATES PATENT OFFICE

ROBERT E. HUMPHREYS, OF WHITING, INDIANA, ASSIGNOR TO STANDARD OIL COMPANY, OF WHITING, INDIANA, A CORPORATION OF INDIANA

ART OF PRESSURE DISTILLATION

No Drawing.

Application filed April 9, 1921. Serial No. 460,002.

The present invention relates to the production of gasoline from heavier hydrocarbon oils under the action of heat and pressure and more particularly to its production from hydrocarbon oil distillates or fractions having a boiling point range between 340° and 600° F.; such as kerosene, naphtha bottoms and the like, which have not been susceptible of cracking under pressure distillation as hitherto practiced.

In accordance with the present invention a hydrocarbon oil distillate having a boiling point range between 340° and 600° F. is placed in a suitable still, for example, one such as that described in my copending application Serial No. 435,700 filed Jan. 7, 1921, and subjected to distillation under pressures in excess of 300 pounds per square inch. For example, I may treat naphtha bottoms, which is a bottom or residue obtained on redistillation of a fraction or distillate containing gasoline, kerosene and heavier oils. An average distillation record of such a material shows a gravity of 35.5 to 36.5° Bé., an initial boiling point of 340°-400° F. and 95 to 98% off at 600° F. The naphtha bottoms are charged into a still and are heated under a pressure in excess of 300 lbs. per square inch, say 325 lbs. The liquid still contents attain a temperature of 740-765° F. The vapors evolved, which contain a large proportion of gasoline constituents, may suitably be condensed under the distillation pressure, or, if desired, under atmospheric pressure or an intermediate pressure between atmospheric and the distillation pressure. The distillate contains a large proportion of gasoline constituents (upwards of 40%) and may be redistilled, for example, with steam, for the separation of the gasoline.

I claim:

The process of manufacturing gasoline which comprises heating naphtha bottoms under a pressure of about 325 lbs. per square inch to a temperature of 740-765° F., condensing the evolved vapors and collecting the distillate.

ROBERT E. HUMPHREYS.
